AUTOMATIC TELEPHONE SYSTEM

Hans P. Boswau, Lorain, Ohio

Original application November 30, 1939, Serial No. 306,929. Divided and this application December 21, 1940, Serial No. 371,065

33 Claims. (Cl. 179—27.54)

The present invention relates in general to automatic telephone systems, and the object of the invention is to produce a new and improved system of this character, which is economical to manufacture, easy to install, and which will give service of high grade with a minimum of maintenance expense.

A special object of the invention is the production of a new and improved switching mechanism for use in automatic telephone systems.

This application is a division of my application, Serial No. 306,929, filed November 30, 1939, on which Patent No. 2,307,757 was granted Jan. 12, 1943.

The invention and various features of improvement comprised therein will be described hereinafter in connection with the accompanying drawings, in which:

Fig. 1 is a partial side view of a single unit of switching equipment;

Fig. 2 is a section on the line 2—2, Fig. 1, drawn to a somewhat larger scale;

Fig. 3 is a top view of the switching unit shown in Figs. 1 and 2, with certain parts broken away;

Figs. 4 to 7, inclusive, are views which show details of the supporting means for certain of the operating bars;

Fig. 8 shows one of the link operating members;

Fig. 9 is a fragmentary view of a switching unit in perspective, intended to facilitate an understanding of the principles on which it operates; and

Fig. 10 is an exploded view of a part of the bank, showing the construction of the contact members and insulators.

Referring now to Figs. 1 to 10, inclusive, the switching unit which is shown in these views will be described.

The various parts of the unit are mounted on a frame which comprises vertical end members 1 and 2, of angle iron, and top and bottom members 3 and 4. The top member 3 is a flat metal plate having upturned end 5, Fig. 1, which is secured to the vertical member 1 by screws, as shown. The opposite end is similarly upturned and is secured to the vertical member 2. The member 3 is also provided with upturned side flanges 6 and 7. The bottom member 4 is similar to member 3 and is provided with downturned ends 8 and 9 which are secured to the vertical members 1 and 2, respectively. The bottom member 4 also has downturned flanges 8 and 9 along the sides. Thus a rigid frame

is provided upon which all the parts of the switching unit are mounted.

The contact bank comprises ten parallel sections extending transversely of the switching unit and supported between the top and bottom plates 3 and 4. There is also a special section at one end of the unit, provided for a purpose which will be described subsequently. The complete bank consists in part of elements individual to each section and in part of common elements, the latter comprising rigid flat conducting bars extending lengthwise of the switching unit through all the sections in series.

The contact bank may be explained more in detail in connection with Figs. 1 and 10. Considering the first regular bank section, there is a rectangular strip of insulation 14 which extends transversely across the bottom plate 4, and on this strip 14 there is placed a similar strip 15. Resting on the latter strip is a strip of conducting material 16, which has a series of eleven contact springs, such as 17, 18, 19, and 20, Fig. 10, formed integrally therewith. The complete strip 16 with its integrally formed contact springs may be punched from a sheet of suitable material. Each of the insulating strips, such as 14 and 15, may have an opening at each end, surrounded by a raised rim on the top of the strip, which is adapted to fit in an opening in a strip such as 16 and a corresponding depression in the bottom of the next insulating strip above. This is a customary expedient used to assist in aligning the bank elements.

Above the conducting strip 16 there is assembled an insulating strip 21, which is similar to 14 except that its upper surface is provided with a plurality of notches for receiving the contact element 22 and a series of ten conducting bars, such as 24, 25 and 26. The element 22 is provided with a terminal lug 23 which extends outside the bank assembly.

There are nine other bank sections to the right of the first section, which are identical with the first section. Fig. 1 shows the second section and part of the third, and also shows a special section at the left of the first regular section. In each of these sections the first fixed contact element at the edge of the bank is a contact element such as 22 which is individual to the section. In the special section and in the second section, Fig. 1, these contact elements are indicated at 51 and 52, respectively. The remaining fixed contact elements on this layer comprise the ten flat conducting bars, such as

24, 25, and 26, which extend through and are common to all the sections. These bars extend beyond the tenth section at the right hand end of the unit, and the projecting ends of the bars form terminals for the attachment of conductors.

The second layer of the bank is similar to the first, and in the case of the first regular section comprises the insulating strip 27, the conducting strip 28 having eleven integrally formed contact springs, such as 35, 36, 37, and 38, and notched insulating strip 29, the fixed contact element 30 provided with lug 31, and ten flat conducting bars, such as 32, 33, and 34, the latter being common to all the sections, like bars 24, 25, and 26 of the first level.

The third layer of the bank is also similar to the first layer, and comprises in the case of the first regular section the insulating strip 39, the conducting strip 40 having eleven contact springs such as 48 formed integrally therewith, the notched insulating strip 41, the fixed contact element 42 having lug 43, and ten flat conducting bars, such as 44, 45, and 46. These bars are common to all the sections.

The conducting bars 44, 32, and 24 constitute a three-conductor line or trunk, bars 44 and 32 being the line bars while bar 24 is the test bar; that is, the two line conductors of a subscriber's line or of a trunk line may be connected to bars 44 and 32, while the test conductor is connected to bar 24. Thus it will be seen that the thirty bars in the first three layers of the bank represent ten three-conductor lines or trunks which are common to all sections of the bank. The three conducting strips 40, 28, and 16 of the first regular section are the three conductors of an intermediate trunk or link circuit which extends across or in coordinate relation to the ten lines or trunks represented by the ten sets of bars, such as 44, 32, 24, etc. Since the other nine regular sections of the bank are similar to the first section, there are in the first three layers of the bank ten of these intermediate link circuits each of which intersects each of the line or trunk circuits. Any link circuit can be connected to any line or trunk circuit by operation of the contact springs at the point of intersection. For example, the link circuit in the first regular section can be connected to the first line or trunk circuit by pressing contact springs 55, 36, and 18 into engagement, respectively, with bars 44, 32, and 24.

There are twenty-seven additional layers in the bank above the first three layers which have been described, making thirty layers altogether. The additional layers may be considered as comprising nine sets of three layers each. In each set of three layers there are thirty bars corresponding to bars such as 44, 32, and 24, representing ten three-conductor lines or trunks. Also in each set of three layers there are thirty conducting strips, such as 40, 28, and 16, three to each of the regular bank sections, and constituting ten three-conductor link circuits. In the complete switching unit there are, therefore, three hundred of the flat conducting bars, such as 44, 32, and 24, representing one hundred three-conductor lines or trunks. There are also three hundred of the transverse conducting strips, such as 40, 28, and 16, arranged thirty to each regular bank section. Each such bank section, therefore, contains ten link circuits and, since there are ten regular bank sections, the total number of link circuits is one hundred.

The method by which the bank is built up may follow known practice in assembling such structures. It may be built up layer by layer on the bottom plate 4, as suggested in the previous description, and before the top plate 3 is assembled in the frame, suitable jigs being used for assisting in keeping the different sections in place as they are being assembled. When all the elements are in place the top plate 3 may be placed 10 in position and pressure can be applied to compress the bank, after which the top plate 3 can be secured to the end members 1 and 2. To give additional security, rods such as 56, Fig. 1, may be provided, passing up through the bottom plate 15 4 and through the openings, such as 49 and 50, in the bank elements and threaded into the top plate 3. There may be one of these rods at each end of each bank section.

As previously mentioned, the line or trunk bars, 20 such as 44, 32, and 24, extend to the right beyond the tenth regular bank section, and the ends of the bars are formed into terminal lugs for the attachment of wires or cable conductors. In Fig. 3 the ends of the top layer of bars can 25 be seen, the end of top plate 3 being broken away. There are twenty-nine similar layers beneath the one shown.

As seen from the sectional view, Fig. 2, the 30 three hundred line or trunk bars form ten vertical rows or groups of thirty bars each. The first group includes bars 24, 32, 44, and twenty-seven other bars in the same vertical row, the second group comprises bars 25, 33, 45, and twenty-seven other bars in the same vertical row, and so on. The numbering of the lines or 35 trunks in each group may be from the top down. The first three bars in the first vertical row may be assigned to the first line or trunk, the next three to the second, and so on, bars 44, 32, and 24 being assigned to the tenth or 0 line or 40 trunk of the group.

As previously mentioned, there are in each of 45 the ten regular bank sections, ten intermediate link circuits, each comprising three conducting strips, such as 40, 28, and 16, which constitute the lowermost or tenth link circuit in the first regular section. This link circuit may be regarded as terminating in the three contact springs 48, 35, and 17, and each of the nine link 50 circuits above terminates in a similar set of contact springs. Associated with the contact springs 48, 35, and 17 there is a set of fixed contacts comprising contacts 42, 30 and 22, provided with lugs 43, 31, and 23, and each of the other 55 sets of contact springs has associated with it a similar set of fixed contacts. The several sets of fixed contacts in the first regular section are all connected in multiple by strapping at the terminal lugs; that is, lugs 43, 31, and 23 are connected, respectively, to the three corresponding lugs of the contact set immediately above, and the latter three lugs are connected, respectively, to the next three lugs above, and so on. The ten contact sets of the first section thus strapped 60 together constitute the multiple terminals of a trunk line, to which any link circuit of the first section may be connected by pressing its terminal contact springs, such as 48, 35, and 17, into engagement with their associated fixed contacts, 65 70 such as 42, 30, and 22.

Each of the nine other regular bank sections 75 is wired just as described in the case of the first regular section, and there are, therefore, ten trunk lines which terminate in multiple connected contact sets in the ten regular bank sec-

tions, respectively. These trunk lines may be outgoing trunk or incoming trunks, depending on the switching stage at which the unit is used.

The special bank section which is shown to the left of the first regular section in Fig. 1 may be the same as the regular sections insofar as the contact elements contained therein are concerned. However, the function of this special bank does not involve the closing of any circuits to the line conductors, and hence the conducting strips which correspond to strips, such as 40 and 28, may be omitted, as indicated in the drawing. Plain metal strips having no contact springs and functioning as spacers may be inserted instead. The first, fourth, seventh, etc. layers are equipped with conducting strips such as 51, having contact springs, such as 53 and 54. At each of these strips the first contact spring such as 53 is bent up and soldered to the individual contact element such as 51 above. The ten lugs, such as 58 and 59, therefore, can be used as terminals for the ten conducting strips such as 51. The conducting strip 51 terminating at lug 58 and having ten contact springs such as 54 constitutes means for extending a connection to the test conductor of any one of the ten lines or trunks of the bottom layer in the bank, and the other similar conducting strips above have the same functions with respect to the lines or trunks in the corresponding layers of the bank.

The mechanism for operating the contact springs of the bank will now be explained, with reference particularly to Fig. 2, which shows a section taken just to the right of the first regular bank section as seen in Fig. 1. Considering the first vertical row of bars, such as 44, 32, and 24, with their associated contact springs, such as 55, 36, and 18, the latter are operated by means of a vertical longitudinally movable operating bar having a plurality of projections thereon equal to the number of contact springs in the vertical row, or thirty altogether. This operating bar comprises a rod 60 on which there is molded a cylindrical body 61 of insulating material having projections, such as 62, 63, and 64. There are ten of these operating bars assigned to the first bank section, as seen in Fig. 2.

The ten operating bars above referred to are provided with bearings which are supported on the top and bottom plates 3 and 4. The top plate is slotted at 67, Fig. 4, and the bottom plate at 68, Fig. 5, to permit the operating bars to be inserted after the bank has been assembled. The bars are, of course, inserted in such a manner that the projections 62, 63, etc. are not interfered with by the bars 44, 32, etc., and are then rotated 90° to the positions in which they are shown. The upper bearing is formed by a notched strip 69 and a strip 70 having a single long recess in one side thereof, these strips being assembled from opposite sides of the row of bars 60 and being secured to the frame plate 3 by means of two screws. As can be seen from Fig. 6, the bars 60 lie in the notches 71 of strip 69 where they are retained by the strip 70. At its lower end each rod 60 has a rectangular bend formed therein, providing a short section such as 66 extending parallel to the main section of the rod, as shown in Fig. 5. The lower bearing is formed of a strip 72, having notches for each rod 60 and its parallel section 66, and a retaining strip 73. These strips are secured to the lower frame plate 4 by means of screws. It will be

clear that the described arrangement prevents rotation of the rods 60.

The contact springs, such as 18, 36, and 55 are tensioned lightly against the projections, such as 62, 63, and 64. The projections 63, 64, etc. rest on the bars 24, 32, etc., which support the weight of the bar 60—61. Each bar is slidable vertically to close simultaneously all the contacts in the associated vertical row. When bar 60 is raised vertically, for instance, all of the thirty contact springs, such as 18 and 36, are pressed into engagement with the corresponding bars 24, 32, etc.

Each of the ten regular bank sections is, of course, provided with a set of ten vertical operating bars similar to those described in the case of the first section. There are, therefore, one hundred of these operating bars.

The mechanism for raising the operating bars will next be described. To accomplish this purpose there is provided at each regular bank section a so-called gate and a magnet for operating it. The gate and associated magnet at the first regular bank section is typical of the others and will be described briefly.

The magnet is indicated at 75 and includes core 76 and pole pieces 77 and 78 secured to opposite ends of the core. The magnet structure is mounted on the bottom plate 4 of the frame by means of brackets 82 and 79 secured to pole pieces 77 and 78 by screws 85 and 86, respectively, and to flanges 9 and 8 by screws 83 and 84, respectively. The magnet has an armature 100, pivoted on brackets 82 and 79 by means of pivot screws 87 and 88, respectively. Armature 100 has two arms 101 and 102, which extend to the right a short distance beyond the pole pieces 77 and 78, as seen in Fig. 1.

The gate comprises two vertical pieces of angle material 91 and 92, which are pivoted on the upturned ends of arms 101 and 102, respectively, by means of pivot screws 89 and 90, said pieces 91 and 92 being held together at the top by a cross member 94. The gate has bearings at the top comprising notches in the ends of strip 69, as shown in Figs. 2 and 6. When magnet 75 is energized, armature 100 is attracted and raises the gate, the vertical side pieces 91 and 92 sliding in the notches in strip 69. When the magnet is released, the gate restores by gravity and comes to rest with projections 106 and 107 engaging flanges 6 and 7 of the top frame plate 3.

The magnet 75 has associated therewith a set of contact springs indicated at 103. The bracket 79 includes a part 80 extending at right angles to part 79 and having a downwardly-extending continuation 81 on which the springs 103 are mounted by means of the usual insulators and screws. The springs are actuated by means of a stud 105 of insulating material carried on the arm 104 of armature 100.

Mounted on the cross member 94 at the top of the gate there is a comb-shaped member 96 provided with the spring fingers such as 97. These fingers are all lightly tensioned to the right against the cross bar 95 which extends across the gate a short distance below cross member 94. Each spring finger 97 is notched at one side, whereby there is formed at the end a lifting arm 98 the upper edge of which is located just to the right of and slightly below the hook 65 on rod 60. The relation between the lifting arms 98 and hooks 65 can be seen clearly from Figs. 1 and 2. These spring fingers and the lifting arms at the

ends thereof are provided for raising the vertical operating bars 60.

As mentioned previously, there is a gate for each regular bank section, or ten gates altogether. From a circuit standpoint the ten gates correspond to the ten trunks, incoming or outgoing, which terminate in the ten bank sections, respectively.

The spring fingers 97 of each gate are all normally ineffective to raise their associated operating bars when the gate is lifted. They are rendered effective selectively by means of a set of ten so-called "tens bars" which will now be described with reference to Figs. 1, 2, and 3.

One of the tens bars is indicated by the reference numeral 111. This bar and nine other similar bars extend lengthwise of the unit in spaced relation just above the upper frame plate 3. The bars are slidably supported at the left in notches in the transverse bar or strip 112 and are retained therein by means of a strip 113. At the right hand end the bars are slidably supported in a notched bar which is similar to bar 112 and are retained in position by a strip 114. All of the ten bars can be seen in Fig. 3, and also in Fig. 2, from which it will be clear that the bars are equal in number to and are spaced with definite relation to the spring fingers such as 97 on the gates.

The bar 111 is forced to the right, as seen in Fig. 1, by means of spring 115 and has an offset portion 116 at the end which limits its movement in this direction by engagement with the edge of strip 113. The spring 115 is compressed between the angle strip 116 at one end and the bar 110 at the other and being slightly longer than the distance between these parts it has a curved formation, as seen in Fig. 1. Each of the other nine bars such as bar 111 is provided with a spring such as spring 115, as can be seen clearly from Fig. 3.

The bar 111 is provided with an upwardly-extending projection or cam 121 which is located just to the right of the lower end of spring finger 97, as seen in Fig. 1, and with nine similar projections or cams, such as 122 and 120, which are located just to the right of the spring fingers corresponding to finger 97 on the nine other gates, respectively. These ten projections on bar 111 are adapted to bend the ten spring fingers such as 97 to the left and beneath the associated hooks such as 65 when the bar 111 is moved longitudinally to the left. Each of the other nine tens bars is similarly provided with ten upwardly-extending projections which are adapted to operate the ten spring fingers in the corresponding row.

The tens bars described in the foregoing are selectively actuated by means of ten magnets, such as 131, 132, and 130, which are mounted on the top frame plate 3 in a manner similar to the way in which magnets 75 are mounted on the lower frame plate 4.

Magnet 131, which is the same as the others, includes the usual core 142 and pole pieces 137 and 138, which are secured to brackets 133 and 136 by means of screws 143 and 144, respectively. The two brackets, in turn, are secured to the flanges 6 and 7 of top plate 3 by means of screws 145 and 146, respectively. The magnet 131 has an armature 231, which is pivoted on brackets 133 and 136 by means of pivot screws 147 and 148, respectively. The armature 231 has an upwardly-extending arm 140, for operating a set of contact springs which has been omitted in order to avoid obscuring the parts beneath it,

and a downwardly-extending part 139 which merges into a transverse member 251, Fig. 1, formed integrally therewith and spanning all the tens bars such as 111.

When the magnet 131 is energized the armature 231 is attracted and the member 251 is moved to the left, coming into engagement with a vertical member 241 riveted to the tens bar 111 and moving bar 111 to the left. Only bar 111 has a vertical member such as 241 associated with member 251 and consequently only the tens bar 111 is actuated by the energization of magnet 131. The next tens bar has a vertical member 242 which is associated with the transverse member 252 actuated by the armature 232 of magnet 132, and each succeeding tens bar has a similar vertical member, which is, however, in each case disposed one position to the right of the corresponding vertical member on the preceding tens bar. Thus the armature of the tenth or last magnet 130, seen in Fig. 3, has a transverse member which cooperates with the vertical member 240 on the tenth or last tens bar. From the foregoing it will be understood that the ten vertical members, such as 241, 242, and 240, are positioned on a diagonal line, viewing the unit from the top, which extends from the first member 241 on the first tens bar to the last member 240 on the tenth tens bar. Each armature such as 231 is provided with a transverse member such as 251 spanning all the tens bars merely for the sake of uniformity, that is, to enable all the armatures to be made alike.

The bracket 133 includes a portion 233 which extends parallel to magnet 131 for a short distance and which has a vertical extension 234 on which a set of contact springs are mounted in conventional manner. These springs are shown in the case of magnet 132, and are indicated by reference character 236. They are operated by the insulating stud 141 on arm 140 of armature 232. Each tens magnet is provided with a similar set of contact springs.

The operation of any tens bar results in the operation of mechanism shown in Figs. 1 and 3 for closing all the contacts in the corresponding vertical row in the special bank section hereinbefore described. The contacts in the row corresponding to tens bar 111 and including contact spring 54 are operated by means of a vertical operating bar comprising a rod 118 and a cylindrical body 119 molded thereon with projections extending underneath the contact springs such as 54. This operating bar may be similar to bar 60-61, Fig. 2, although only one-third of the side projections are used. The bar 118-119 is supported in bearings the same as bar 60-61 and the other bars in the same transverse row. The upper end of rod 118 is bent at right angles to the main portion of the rod and the short horizontal section thus formed carries a roller 117 which rests on the spring 115. When the tens bar 111 is actuated, that is, moved to the left, the spring 115 assumes a greater curvature and the roller 117 is raised, carrying with it the operating bar 118-119. Thus all the contact springs such as 54 in the vertical row are operated.

There are nine other operating bars similar to bar 118-119, all located in the same transverse row. The rollers such as 117 for operating these bars can be seen in Fig. 3.

It will be recalled now that each of the regular bank sections includes ten intermediate link circuits extending transversely of the unit. The

lower link circuit of the first section comprises the conducting strips 40, 28, and 16, and terminates in the contact springs 48, 35, and 17, these three springs constituting a set. There are nine similar sets in a vertical row above the set of springs 48, 35, and 17. The means for selectively operating these sets of contact springs will now be described.

There are ten operating members for the ten sets of contacts above referred to, each member comprising a recessed block of insulating material having projections thereon for operating the associated contact springs. Fig. 2 shows the first and second blocks 160 and 161, and the last block 162. Block 160 will be described in detail. It may be molded in one piece of some plastic compound and has three projections 166, 167, and 168 which extend beneath the three contact springs 172, 173, and 174, respectively, of the associated set. These projections rest, respectively, on the three contact members, such as 176 and 177, which are immediately beneath them. On the side opposite the projections 166-168, the block 160 is recessed as indicated at 170, Figs. 2 and 8. There is also a longitudinal slot 169, having the same depth as recess 170. The slot 169 is of the proper width to receive the lateral extension 93 of the side angle member 91 of the gate. As shown in Fig. 2, this member is wider where it passes the bank, the inwardly-extending portion being indicated at 93. The block 160 is thus loosely supported by the gate in the position shown in Fig. 2, with its weight resting on the contact members such as 176. The other blocks, such as 161 and 162, are supported the same way. It will be understood that when the gate is raised the part 93 thereof slides in the slots 169 of the several blocks and these blocks remain stationary. Means is provided, however, for moving a selected one of the blocks along with the gate when it is raised. The selecting means includes a set of ten so-called "units bars" which will now be described.

Seven of the ten units bars are shown in Fig. 1. The first two bars are indicated at 181 and 182, and the last or tenth bar at 180. For the purpose of supporting these bars there are provided two vertical strips 187 and 189 which in turn are supported on angle pieces 186 and 188, the latter being secured to the flanges 7 and 9 on the top and bottom plates of the frame. The angle piece 186 not only supports the strip 187, but also supports the units magnets, as will be explained presently. The strips 187 and 189 are slotted on the side toward the unit and the slots are deep enough to extend some distance beyond the edges of angle pieces 186 and 188, thus forming rectangular slots for receiving the bars, such as 181, 182, and 180, as shown in Fig. 2. The bars fit loosely and are movable longitudinally to the left, as seen in Figs. 1 and 3. Each bar has a series of ten projections, such as 183, 184, and 185, which cooperate with spring fingers on the gates for operating the blocks such as 160.

The particular block 160 is actuated by means of a spring finger 163, shown in Figs. 2 and 8. At its upper end the spring finger 163 is attached to the angle piece 91 of the gate for the first section. From its point of attachment to the gate the main body of the finger extends angularly downward until a point outside the block 160 is reached after which it extends vertically downward and terminates in an angularly disposed lifting arm 164, which extends to the right, as seen in Fig. 2. Just above the lifting arm 164

and in alignment with the projection 183 on bar 181 there is a projection or arm 165, which extends through opening 190, Fig. 1, in the gate. The parts 164 and 165 are formed integrally with the spring finger 163, which may be punched from a sheet of suitable material and bent to the shape shown.

When the units bar 181 is moved longitudinally to the left, the projections 183, 184, etc., engage the projections 165, 165', etc. on the upper spring fingers of all the gates and move them into operative relation to the associated blocks such as 160. The projection 183, for example, engages projection 165 and bends spring finger 163 far enough so that the lifting arm 164 enters the recess 170 of the block. Now if the gate 91-92 is raised, the angularly disposed lifting arm 164 will engage the surface 171 defining the upper side of the recess and will raise the block along with the gate, thereby pressing the contact springs 172, 173, and 174 into engagement with their associated contact members such as 175. The other blocks, such as 161 and 162, remain unoperated.

The ten units bars such as 181 are selectively operated by means of a set of ten magnets which are mounted at the left hand end of the unit on the vertical angle piece 186. The magnet 211, associated with the first tens bar 181, comprises the usual core and a heel piece 201, the latter being secured to the angle piece by means of screws 209 and 210. The armature 202 has a knife edge pivot on the end of the heel piece 201, and is provided with an extension 203 the end of which engages a notch in the end of bar 181. It will be seen that when magnet 211 is energized, the armature 202 will be attracted and bar 181 will be moved longitudinally to the left by means of the armature extension 203.

Magnet 211 also operates a set of contact springs by means of the insulating pin 204 secured to the armature 202. These contact springs are mounted on a bracket which forms part of heel piece 201 and comprises a part 205 bent at right angles to the main body of the heel piece and a part 206 which is bent at right angles to part 205 and which is parallel to the heel piece. The springs are secured to the part 206 by means of the usual insulators and screws. A spring 207 is inserted next to 206 and serves to retain the armature 202 in position.

As shown clearly in Fig. 1, each of the other units bars such as 182 has associated with it an operating magnet such as 212 which is similar to magnet 211.

It should be stated that the sets of contact springs which are shown associated with the gate magnets, tens magnets, and units magnets are to be considered merely as indicating that each of these magnets may have and operate a set of contact springs in addition to performing its other function. The exact spring combination used in any case will depend on the switching stage at which the unit is used and may vary even at each stage.

The mechanical details of establishing a connection by means of the described switching unit can perhaps be best understood by reference to Fig. 9, which shows in perspective a part of the first regular bank section and part of the associated gate 91. It may be assumed that there are one hundred lines terminated in the switching unit, the line numbered 11 being terminated in the bars 185, 186, and 187. There may also be ten trunks terminated in the unit, the first trunk being connected to contact members 175, 176, and

177, which are multiplied to the other similar sets of contact members in the same vertical row, as previously described. In order to connect line 11 to the first trunk line, the tens bar 111 and the units bar 181 are actuated, followed by lifting the gate 91.

When tens bar 111 is moved to the left, its projection 121 engages the end of spring finger 97 and bends the spring far enough so that lifting arm 98 passes beneath the hook 65 on vertical operating bar 60—61. When units bar 181 is moved to the left, the projection 183 thereon engages arm 163 on spring finger 163 and bends the latter far enough so that lifting arm 164 passes underneath the edge 171 of the recess in block 160. Now when the gate 91 starts to rise, lifting arm 98 engages the hook 65 and slides along the hook a short distance until the arm engages the vertical portion of rod 60. The slight additional bending of spring finger 97 which is involved in this operation moves arm 98 away from projection 121. At the same time the angularly disposed lifting arm 164 engages the inclined surface 171 on block 160 and slides along said surface until the lower end of spring finger 163 engages the angle piece 91 of the gate, thus moving arm 163 away from projection 183. Further movement of the gate now results in the raising of operating bar 60—61 by the lifting arm 98 and the raising of block 160 by the lifting arm 164.

The operating bar 60—61, when raised as described in the foregoing, connects the ten lines terminating in the first vertical row of line bars to the ten intermediate link circuits in the first bank section, and more in particular it connects the line 11 to the uppermost or first link circuit by pressing contact springs 192, 193, and 194 into engagement with bars 195, 196, and 197, respectively. The first link circuit terminates in contact springs 172, 173, and 174, which are pressed into engagement with contact members 175, 176, and 177, respectively, by the block 160. Thus the line and trunk are connected.

The connection is maintained by the gate 91, which remains in operated position. The tens bar 111 and the units bar 181 are released as soon as the gate has operated. The spring finger 97 is retained in operative relation to bar 60—61 by the hook 65, and likewise the spring finger 163 is retained by the inclined surface 171 on block 160. When the gate is restored, the operating bar 60—61 and the block 160 are positively restored by the tension in the operated contact springs, such as 192 and 172. On complete restoration of the gate, the lifting arms 98 and 164 drop below hook 65 and surface 171, respectively, and the spring fingers 97 and 163 are permitted to restore.

As many as ten connections may be in existence simultaneously; that is, all ten of the trunks associated with the ten bank sections may be in use at the same time. The establishment of all these connections is controlled by the tens and units bars, which are common to the ten gates. Further details of the way in which connections are established, dealing more particularly with the circuits involved, will be found in my Patent No. 2,307,757, previously referred to, which contains a description of the complete telephone system and its operation.

The invention having been described, that which is believed to be new and for which the protection of Letters Patent is desired will be pointed out in the appended claims.

I claim:

1. In a switching mechanism, a group of bars constituting line or trunk terminals, said group being divided into sub-groups arranged in parallel planes, a plurality of intermediate links associated with each sub-group of bars, each link comprising a continuous metal strip extending across the bars of the associated sub-group and having an integrally formed contact finger at the point where it crosses each bar, each strip having also an additional integrally formed contact finger at one end, said links being divided into sub-groups located in parallel planes and each sub-group including links associated with different sub-groups of bars, a group of multiple connected trunk contacts associated with the additional contact fingers of each sub-group of links, means for simultaneously actuating the proper contact fingers to connect the links of any sub-group to corresponding individual bars of all the sub-groups of bars, and means for individually operating said additional contact fingers to connect any link in the connected sub-group to its associated trunk contact independent of the remaining links in such sub-group.

2. In a switching mechanism, a contact bank comprising a plurality of sections, contact bars extending through all said sections and arranged in groups occupying superimposed parallel planes, a plurality of contacts individual to each section and located in the planes of said bars, a group of continuous contact strips in each section extending across the bars of said groups, respectively, each strip having an integrally formed contact finger for each bar it crosses and an additional integrally formed contact finger for the contact which is in the plane of the bars, operating means individual to each section for actuating said contact fingers, and means comprising selecting bars common to all the sections for selecting contact fingers to be operated.

3. In a switching mechanism, sets of contacts arranged in superimposed horizontal rows, a plurality of vertical operating bars common to said rows and equal in number to the number of contact sets in each row, a contact set at the end of each row, individual operating members for said last mentioned contact sets, means for selecting an operating bar and one of said operating members, and a common means for actuating the selected bar and member.

4. In a switching mechanism, a plurality of bank sections arranged in parallel planes, continuous contact strips common to all said sections, continuous contact strips individual to each section, each said individual contact strip extending successively across a plurality of said common contact strips, sets of contacts in each section associated with said last mentioned strips only, a group of operating bars individual to each section for effecting connection between the strips individual to the section and the common strips, operating members for the said contact sets at each section, a set of bars common to all sections for selecting operating bars, a second set of bars common to all sections for selecting operating members, and means for actuating a selected operating bar and operating member at any desired section.

5. In a switching mechanism, a plurality of bank sections including a special bank section, each section including sets of contacts, contact operating bars in each section, selecting bars, means whereby each selecting bar when actuated selects corresponding operating bars for ac-

tuation in all said sections except said special section, means whereby each selecting bar when actuated also actuates the operating bar in the special section which corresponds to the operating bars selected in the other sections, and means for actuating any selected operating bar.

6. In a switching mechanism, two banks of contacts, two operating bars for actuating contacts in said banks, respectively, a selecting bar, means responsive to the operation of said selecting bar for selecting one of said operating bars for actuation and for simultaneously actuating the other operating bar, and means for actuating the selected operating bar.

7. In a switching mechanism, a row of longitudinally movable contact operating bars, a common member movable in the same direction as said bars, said member including a number of flexible fingers equal in number to the number of operating bars, a plurality of selecting bars, each adapted to bend one of said fingers into operative relation to the corresponding operating bar, means for actuating any selecting bar, and means for moving said common member to cause the finger which has been flexed by the selecting bar to engage and move the associated operating bar.

8. In a cross bar switch, a longitudinally movable group selecting bar, a bow-shaped spring arranged to oppose movement of said bar, said spring being compressed lengthwise between one end of said bar and a fixed support, a connecting bar operated by the increase in the curvature of said spring when said selecting bar is operated, and means connecting the central portion of said spring with said connecting bar to operate the same as set forth.

9. In a cross bar switch, a first set of bars for actuating line and test contacts, a second set of bars for actuating test contacts only, a third set of bars for selecting bars of the first set for actuation, means responsive to the operation of any selecting bar for operating a bar of the second set, and means for actuating any selected bar of the first set.

10. In a cross bar switch, a longitudinally movable selecting bar, first and second longitudinally movable contact actuating bars arranged parallel to each other and perpendicular to said selecting bar, means responsive to the operation of said selecting bar for operating the first contact actuating bar, an operating device for the second contact actuating bar moved into operative relation therewith by operation of said selecting bar, and means for operating said device subsequent to operation of said selecting bar.

11. In a cross bar switch, two longitudinally movable operating bars each adapted to close a plurality of sets of contacts, two devices for actuating said bars, respectively, the second of said devices being normally inoperative to actuate its associated operating bar, means including a longitudinally movable selecting bar for operating the first device to cause the same to actuate the associated operating bar and for simultaneously rendering the second device operative, and independent means for operating said second device to cause the same to actuate its associated operating bar.

12. In a cross bar switch, two contact actuating bars, individual means for operating each said bar, and a selecting bar effective when operated to prepare for operation the individual means associated with one of said contact actuating bars and to operate the individual means associated

with the other of said contact actuating bars.

13. In a cross bar switch, a plurality of groups of contact sets, each set comprising line contacts and a test contact, a plurality of groups of test contacts corresponding, respectively, to said groups of contact sets, a first set of bars for actuating the groups of contact sets, respectively, a second set of corresponding bars for actuating said groups of test contacts, respectively, a third set of bars, and means responsive to the operation of any bar in said third set for selecting a bar of the first set and for operating the corresponding bar of the second set.

14. In a cross bar switch, a group of longitudinally movable selecting bars arranged parallel to each other in spaced relation, a group of individual operating magnets for said bars, said magnets being arranged in a row which extends above and parallel to said bars, and actuating members for the bars operated by said magnets and spaced apart along the group in accordance with the location of said magnets.

15. In a cross bar switch, a row of vertical operating bars each adapted to close a plurality of sets of contacts, a common actuating device for said bars comprising vertical side members at opposite ends of said row and a horizontal cross member connecting said side members at the top, a magnet having an armature connected to said side members at the lower end thereof and adapted to raise said device, individual members for lifting said bars supported on the said cross member of said device, and selecting means for rendering any one of said individual members effective to lift the associated bar upon the raising of said device by said magnet.

16. In a cross bar switch, a plurality of vertical operating bars disposed parallel to each other in a row, each bar having means for closing a plurality of sets of contacts, a corresponding plurality of lifting devices arranged in a row at the upper ends of said operating bars, a plurality of selecting bars each having means for moving one of said lifting devices into operative relation with the associated operating bar, and means for moving all said lifting devices upward in the plane of said operating bars and thereby cause a lifting device which has been moved by a selecting bar to raise the associated operating bar.

17. In a cross bar switch, a plurality of vertical longitudinally movable operating bars disposed parallel to each other in a row, each bar having means for closing a plurality of contact sets and terminating in a hook at its upper end, a comb-like member extending above and parallel to said row of bars and having flexible depending tongues corresponding to said bars, respectively, means comprising selecting bars for flexing any one of said tongues into operative relation with the hook on the associated operating bar, and means for moving said comb-like member vertically upward to cause the flexed tongue to actuate its associated operating bar by engaging the terminating hook thereof.

18. In a cross bar switch, a plurality of longitudinally movable operating bars disposed parallel to each other in a row, each bar having means for closing a plurality of sets of contacts, a row of normally ineffective individual actuating members for said bars, means including selecting bars for independently moving any actuating member into operative relation with its associated operating bar to select such bar for actuation, and means for moving all said actuating mem-

bers simultaneously, whereby the selected operating bar is actuated.

19. In a cross bar switch, the combination with a plurality of rigid and movable contact members arranged alternately in a row, of an operating bar for said movable contact members comprising a metallic rod extending parallel to said row and having a continuous molded body formed thereon including projections extending laterally into said row in operative relation to said movable contact members, and means for producing a longitudinal movement of said bar to cause said projections to move said movable contact members into engagement with the adjacent fixed contact members, respectively.

20. In a cross bar switch, a plurality of rigid and flexible contact members arranged alternately in a row, said contact members constituting groups of contact sets, a plurality of longitudinally movable contact actuating members arranged in spaced relation end to end along said row, there being one such actuating member to each group of contact sets, a common longitudinally movable operating member extending parallel to said row and provided with individual devices for lifting said actuating members, and means comprising selecting bars for rendering any one of said individual devices operative to lift the associated actuating member responsive to movement of said common operating member.

21. In a cross bar switch, a plurality of fixed and movable contacts arranged alternately in a vertical row, a molded block having a vertical groove in one side and a plurality of projections on the other side extending into said row beneath the movable contacts, one or more of said projections resting on fixed contacts to support the block, a member slidable vertically in said groove, and selectively controlled means on said member for lifting said block to actuate said movable contacts.

22. In a cross bar switch, a plurality of built-up bank sections spaced apart in parallel planes, each bank section comprising a plurality of strips of insulating material clamped together in superimposed relation, a plurality of superimposed spaced groups of rigid metallic bars extending through all said bank sections, the bars of each group being supported at each section between adjacent insulating strips, a plurality of flexible metallic strips extending parallel to the insulating strips in each bank section and crossing said groups of bars, respectively, each strip being clamped between two adjacent insulating strips, and a plurality of integrally formed contact fingers projecting from the edge of each said flexible strip in operative relation to the bars of the associated group.

23. In a cross bar switch, a plurality of strips of insulating material extending parallel to each other in spaced relation, a plurality of flexible metallic strips superimposed on said insulating strips, respectively, each strip having integrally formed spaced contact fingers projecting from one edge thereof, a second plurality of insulating strips superimposed on said flexible strips, respectively, the strips of said second plurality having transverse notches in their upper surfaces which are in alignment with said contact fingers, a plurality of rigid metallic bars arranged perpendicular to all said strips and resting in said notches, a third plurality of insulating strips superimposed on the said second plurality and resting on said bars, all said parts constituting one bank layer, a plurality of similar layers su-

perimposed on said first layer, and means for clamping said layers together.

24. In a cross bar switch, a plurality of parallel bars arranged in superimposed groups, a plurality of flexible metal strips, one for each group of bars, each strip extending across the bars of the associated group and having an integrally formed flexible contact finger at the point where it crosses each bar, the contact fingers of each strip extending at right angles thereto and parallel to the bars of the associated group, means for supporting said bars and strips in fixed relation to each other, and means for simultaneously flexing a contact finger of each strip into engagement with the associated bar.

25. In a cross bar switch, a plurality of contact sets arranged in equal groups, a second plurality of contact sets equal in number to the number of contact sets in one of said groups, continuous conducting strips having integrally formed contacts and connecting each contact set of said second plurality with a contact set in each of said groups, the said integrally formed contacts constituting contacts of the contact sets connected, means including selecting bars for selecting one of said groups of contact sets and an individual contact set of said second plurality, and means including an electromagnet common to all said contact sets for simultaneously closing all the contact sets of the selected group and the selected individual contact set.

26. In a cross bar switch, a plurality of pairs of contacts, each pair including a fixed contact and a movable contact, said pairs being arranged in equal groups, a second plurality of pairs of fixed and movable contacts equal in number to the number of pairs in one of said groups and the movable contact of each pair being formed integrally with corresponding movable contacts in each of said groups, means including selecting bars for selecting one of said groups and an individual contact pair of the second plurality, and means including an electromagnet common to all said contact pairs for simultaneously moving the movable contacts of all the selected pairs into engagement with their associated fixed contacts.

27. In a cross bar switch, a plurality of trunking sections, multiple connected trunk contacts at each section, continuous conducting bars common to all trunking sections and arranged in groups, continuous conducting strips individual to said trunking sections, each strip intersecting one bar of each of said groups and having integrally formed contact fingers for cooperation therewith, also a similar contact finger for cooperation with one of said trunk contacts, and means at each trunking section for operating the proper contact fingers to connect the individual strips at such section with the bars of one of said groups, respectively, and to simultaneously connect one of the connected strips to the associated trunk contact, said means including individual separately operable devices for connecting said strips and trunk contacts, whereby any one of the connected strips may be connected to the associated trunk contact by operation of its individual device while the other strips remain disconnected from their associated trunk contacts.

28. In a cross-bar switch, a plurality of groups of longitudinally movable operating bars, each group comprising a plurality of such bars arranged side by side and parallel to each other in a row, a plurality of sets of contacts arranged for operation by each bar responsive to longitudinal movement thereof, said contact sets in-

cluding continuous contact bars each common to a plurality of contact sets which are associated with operating bars in different rows, a row of individual actuating members for each row of operating bars, selecting bars common to said rows of actuating members, each selecting bar having means for effecting operative relation between one actuating member in each row and its associated operating bar, and means for moving all the actuating members in any row to the exclusion of those in the other rows, whereby a particular selected operating bar is actuated.

29. In a cross-bar switch, a plurality of bank sections each including a plurality of continuous conducting strips in superimposed spaced relation, means in each bank section for establishing connections simultaneously to all the strips in such section at any one of a plurality of points along the length thereof, the said strips in each section being arranged in sets, each set including a plurality of strips, a row of individual devices at the end of each bank section for establishing connections to the said sets of strips, respectively, in such bank section, a plurality of selecting bars common to all said rows of devices, each selecting bar when operated being effective to prepare for operation one device in each said row, a common operating mechanism for the devices in each row, and means for operating any one of said operating mechanisms to actuate any particular one of the devices prepared for operation by an operated selecting bar.

30. A switch structure of box-like conformation, comprising transverse contact bank sections spaced apart lengthwise of the structure, continuous contact bars extending through all said bank sections, said contact bars being divided into groups, continuous contact strips in each bank section common to all the groups of contact bars, said contact strips constituting connecting links, group selecting bars common to said sections, each selecting bar being operative to select a group of contact bars for connection to the links at all sections, contacts at each section individual to the links at such section, respectively, link selecting bars common to all said sections, each link selecting bar being operative to select a link at each section for connection to its associated individual contact, means for operating any group selecting bar and any link selecting bar, connecting means at each section for closing the connections at such section selected by the operated selecting bars, and means for operating the connecting means at any section independent of the connecting means at the other sections.

31. A switch structure of box-like conformation, comprising transverse contact bank sections spaced apart lengthwise of the structure, continuous contact bars extending through all said bank sections, said contact bars being divided into groups, tens selecting bars common to said

sections for selecting groups of contact bars, means in each section for extending connections simultaneously to a selected group of contact bars, units selecting bars common to said sections for selecting an individual contact bar in the selected group, means in each section for extending a connection to such selected contact bar, said last mentioned connection including in series therewith one of said first mentioned connections, and means for operating the said connecting means in any section independent of the connecting means in the other sections.

32. In a cross-bar switch, a plurality of regular bank sections each comprising a plurality of continuous strips having integrally formed contact fingers projecting from the edge thereof, the strips of each section being arranged one above the other in spaced relation, a special bank section comprising a lesser number of strips which correspond, respectively, to certain of the strips in said first mentioned sections, continuous contact bars extending through all said bank sections in operative relation to the contact fingers in said regular bank sections, certain of said bars also being in operative relation to the contact fingers in said special bank section, operating bars for each bank section, each bar adapted to move a plurality of contact fingers into engagement with the corresponding contact bars, tens magnets for selecting operating bars in said regular bank sections for operation, means responsive to the energization of any tens magnet for actuating an operating bar in said special bank section and for selecting an operating bar in each regular bank section, and means for subsequently operating the selected operating bar in any regular bank section.

33. In a cross-bar switch, a plurality of groups of continuous contact bars, each group of bars comprising a plurality of sets of bars, and each set including two line bars and a test bar, a plurality of regular bank sections, each comprising continuous strips extending across the line and test bars of all said groups, a special bank section comprising continuous strips extending across the test bars of said groups, operating bars in each regular bank section each adapted to effect engagement between the strips at the associated bank section and a group of contact bars, operating bars at said special bank section each adapted to effect engagement between the strips thereat and the test bars of a group of contact bars, tens magnets for selecting operating bars in said regular bank sections, means responsive to the energization of any tens magnet for actuating an operating bar in said special bank section and for selecting for operation an operating bar in each regular bank section, and means for actuating the selected operating bar in any regular bank section to the exclusion of the selected bars in the other regular bank sections.

HANS P. BOSWAU.
